(57) **CLAIM**

I claim the ornamental design for an angled bracket, as shown and described.

DESCRIPTION

FIG. 1 is a top right perspective view of the angled bracket;

FIG. 2 is a front view thereof;

FIG. 3 is a bottom view thereof;

FIG. 4 is a top view thereof;

FIG. 5 is a rear view thereof;

FIG. 6 is a left view thereof; and,

FIG. 7 is a right view thereof.

The dashed lines throughout all figures represent portions of the design that form no part of the claim.
